LOREN W. PENNEY, OF NEWTON, MASSACHUSETTS, ASSIGNOR TO SACO-LOWELL SHOPS, OF BOSTON, MASSACHUSETTS, A CORPORATION OF MASSACHUSETTS.

CARDING-ENGINE.

1,307,415.

Specification of Letters Patent. Patented June 24, 1919.

Application filed July 12, 1918. Serial No. 244,640.

To all whom it may concern:

Be it known that I, LOREN W. PENNEY, of Newton, in the county of Middlesex and State of Massachusetts, a citizen of the 5 United States, have invented a new and useful Improvement in Carding-Engines, of which the following is a specification.

In an application heretofore filed by me on November 20, 1917, Serial No. 204,593, I 10 have described a means for cleaning both the cylinder card and the doffer by the one stripping brush, which is located between the two and may be moved into engagement with either. My present invention relates 15 more particularly to the mounting of the stripping brush. Whereas in my former case I mounted the stripping brush upon rockable arms, in the present case I mount the stripping brush in a frame which may 20 be moved horizontally to carry the brush into contact with either the card on the cylinder or the card on the doffer and provide means for so moving it.

My invention will be understood by reference to the drawings, in which—

Figure 1 is a side elevation of a mechanism embodying my invention;

Fig. 2 being a vertical section through the mechanism shown in Fig. 1, the stripping 30 brush being in neutral position, and

Fig. 3 showing a similar section with the stripping brush in position to strip the cylinder card;

Fig. 4 being a longitudinal partial section 35 through the axis of the stripping brush.

The parts of an ordinary carding engine are only shown and described in so far as they are necessary to indicate the application of my invention thereto.

40 A is that part of the casing which covers the cylinder A², A¹ being that part of the casing which covers the doffer A³.

On each side of the machine is a bracket B mounted on the cylinder casing A, this 45 construction being also hook-shaped, its hooked end being shown at b providing a guideway b¹ in which the bushings carrying the stripping brush shaft may be moved horizontally. The stripping brush is shown 50 at C and is preferably of the character described in my above-named application, being mounted on a shaft c carrying a pulley c¹ at one end thereof by which power may be applied to rotate it. This shaft c runs

through two bushings D one at each end, 55 each lying in a guideway forming part of a plate E connected to the side of the nozzle E¹, this nozzle being shown in my previous application. This plate also has bearings F at each end thereof through which passes a 60 shaft F¹ having a handle F² at one end thereof by which it may be turned, and on this shaft at each end thereof and bearing against the hook pieces b of the brackets B on the one side and the abutments b³ on the 65 other side is an eccentric F³, which is mounted on the shaft F¹. It will be seen from this construction that the turning of the handle F² and hence the turning of the eccentric F³ will move the plate E of the nozzle together with the nozzle backward and forward horizontally, and hence will move the stripping brush C either toward the doffer or toward the cylinder card, or, as shown in Figs. 1 and 2, leave it in neutral 70 position, the bushings D of the shaft being thereby slid along the guideways in the bracket. At e is an adjustable screw stop 75 which is adapted to engage the bushings and prevent the stripping brush from being moved too far into the clothing of the doffer. e¹ is an adjusting screw to adjust the position of the bracket B after which the bracket is clamped by the nut b''.

The nozzle E¹ is mounted as described in 85 my previous application and carries on its rear lower surface a foot-piece e² which may be set into a suitable indentation a in the top surface of the casing or cover A¹ to steady it.

90 The nozzle E¹ is connected with a pipe E² up through which the strips are drawn by a suction fan or pump. As it is desirable that when the stripping brush is not in use this passage should be closed, I have provided a gate or damper G of sufficient length and suitably mounted to slide horizontally and so close the opening E³ between the nozzle E¹ and the pipe E², and this gate is 95 operated by the handle lever G¹, which is suitably pivoted at g near the bottom of the pipe E² and is connected by a link G³ pivoted to e¹ at g³ with arms G⁴ sliding with the gate in suitable guideways G⁵ (one of which only is shown). It will be understood 100 of course that while the nozzle E¹ extends entirely across the machine, that is, is of the same length as the stripping brush, the pipe

E^2 projects upward from the center of the nozzle only and is of comparatively small diameter as shown.

I provide an opening G^6 midway between the ends of the nozzle, and I prefer to provide a closure G^7 , which is hinged at g^1 to the lower end of the pipe E^2 and rests upon a part g^2 mounted on top of the nozzle so that access may be had to the interior of the pipe E^2 .

It will be seen from Fig. 3 that when the handle G^1 has been turned through an angle of say 180° approximately from the position shown in Figs. 1 and 2 to the position shown in Fig. 3, the gate G is moved so as to open the entrance from the nozzle into the pipe E^2 .

When the stripping brush is in operation, as the strips are withdrawn by suction, there must be an opportunity for air to pass freely into the entrance of the nozzle carrying the strips with it. I have provided a cover H , which in Fig. 3 is shown open, and in Figs. 1 and 2 is shown closed as would be desirable when the stripper is not in use. This cover H is so shaped that when in place it completes the peripheral portion of the casing A to the cylinder, and it is hinged at h to a bracket H^1 which is pivotally connected by the arm H^2 with the handle G^1 . This bracket H^1 is mounted on a plate H^3 pivotally connected to a bracket h^1 loosely mounted on the shaft F^1 , this construction being such that when the handle G^1 is in its lower position shown in Fig. 2 the cover H is in position to form part of the casing a and so close in the cylinder A^2 (see Fig. 2). A plate H^4 hinged at h^2 to the plate H^3 closes the opening between the nozzle and the chamber containing the stripping brush when the stripping brush is not in use. When, however, the stripping brush is in use, whether in stripping the doffer or in stripping the cylinder card, the handle G^1 being drawn up into the position shown in Fig. 3 to open the gate G , also draws back the cover H lifting it and opening it at its upper end so as to allow a free passage for the brush to have working engagement with the cylinder card. Moreover, this action also lifts the plate H^3 so that there is ample access of air for the nozzle E^1 . The handle G^1 and arm H^2 being then substantially in line the parts are locked in place. Of course the lower the handle G^1 is depressed from its position in Fig. 3, the more secure will be the locking of the parts.

I prefer to provide a narrow guide plate H^5 at each end of the machine so that in dropping the cover H into place its lower end will engage these guide plates and be guided into its closing position.

It has seemed unnecessary to show the stripping brush C in contact with the doffer, but it will be easily understood that upon

turning the handle F^2 from its position in Fig. 3 through an angle of 90 degrees to the left the nozzle and the plates E attached to its end and in which the stripping brush is mounted will by means of the eccentric be drawn to the left, so that the stripping brush will enter the card on the doffer A^2 , it being remembered that the bearing of the shaft F^1 carrying the eccentric F^3 is always in fixed position with relation to the nozzle. The hinging of the cover H at h not only allows it to find its place as part of the casing of the cylinder, but also allows it to be lifted into such position as not to interfere with the stripping of the card by the stripping brush.

The above I believe is the preferable embodiment of my invention, but I do not mean to limit myself thereto, its purpose being the mounting of a stripping brush as part of a carding engine in such a way that without rocker arms, which must project more or less outside the planes of the casings A and A^1 , I mount the stripping brush practically within the machine itself. And while the mounting of the casing H is shown in its preferred form, other means may be provided for the purpose.

What I claim as my invention is:—

1. In a machine of the kind described, a cylinder, a doffer, guideways located between said cylinder and said doffer, a rotary stripping brush, a mounting for said brush at each end thereof, said mountings being mounted in said guideways.

2. In a machine of the kind described, a cylinder, a doffer, guideways located between said cylinder and said doffer, a rotary stripping brush, a mounting for said brush at each end thereof, said mountings being mounted in said guideways, and means for locking said mountings in said guideways.

3. In a machine of the kind described, a cylinder, a doffer, guideways located between said cylinder and said doffer, a rotary stripping brush, a mounting for said brush at each end thereof, said mountings being mounted in said guideways, and means for moving said mountings along said guideways.

4. In a machine of the kind described, a cylinder, a doffer, guideways located between said cylinder and said doffer, a rotary stripping brush, a mounting for said brush at each end thereof, said mountings being mounted in said guideways, and means for moving said mountings along said guideways, said means comprising stationary abutments at each end of said guideways and eccentrics located between said abutments and means for mounting said eccentrics to engage said stripping brush mountings.

5. In a machine of the kind described, a cylinder, a doffer, guideways located be-

- 5   between said cylinder and said doffer, a rotary stripping brush, a mounting for said brush at each end thereof, said mountings being mounted in said guideways, and means for moving said mountings along said guideways, and adjustable stops to limit the movement of said mountings.
- 10   6. In a machine of the kind described, a cylinder, a doffer and a nozzle, guideways located between said cylinder and said doffer, a rotatable stripping brush mounted to be moved in said guideways, and means for moving it connected to the end of said nozzle.
- 15   7. In a machine of the kind described, a cylinder, a doffer and a nozzle, guideways located between said cylinder and said doffer, a rotatable stripping brush mounted to be moved in said guideways, and means for moving it connected to the end of said nozzle, said guideways having abutments and said means comprising a shaft carrying eccentrics supported at the end of said nozzle, said eccentrics engaging said abutments, whereby the rotation of said eccentrics against said abutments will move said brush mountings along said guideways and will also move said nozzle.
- 20   8. In a machine of the kind described, a stripping brush, a nozzle located to receive the strips therefrom, a pipe connected thereto whereby the strips may be carried away, a gate adapted to open or close the passage between said nozzle and said pipe, and means for operating said gate.
- 25   9. In a machine of the kind described, a cylinder, a doffer, a rotatable stripping brush and means for permanently supporting it between said cylinder and said doffer, a nozzle to receive strips removed by vacuum from said stripping brush, and a cover for said cylinder adapted to be removed to allow access to the cylinder.
- 30   10. In a machine of the kind described, a cylinder, a doffer, a rotatable stripping brush and means for permanently supporting it between said cylinder and said doffer, a nozzle to receive strips removed by vacuum from said stripping brush, a pipe for receiving the strip from the nozzle and removing it, a gate to close the connection between said nozzle and said pipe, a cover for said cylinder adapted to be removed therefrom and connections between said gate and said cover, whereby the opening and closing of the gate will open and close said cover.
- 35   11. In a machine of the kind described, a cylinder, a doffer, a rotatable stripping brush and means for permanently supporting it between said cylinder and said doffer, a nozzle to receive strips removed by vacuum from said stripping brush, a cover for said cylinder adapted to be removed to allow access to the stripping brush.
- 40   12. In a machine of the kind described, a stripping brush, a nozzle located to receive the strips therefrom, a pipe connected thereto whereby the strips may be carried away, a gate adapted to open or close the passage between said nozzle and said pipe, and means for operating said gate, a cover for said cylinder adapted to be moved to allow access to the cylinder and means connecting said gate and said cover whereby they may be moved simultaneously.
- 45   13. In a machine of the kind described, a stripping brush, a nozzle located to receive the strips therefrom, a pipe connected thereto whereby the strips may be carried away, a gate adapted to open or close the passage between said nozzle and said pipe, and means for operating said gate, a cover for said cylinder adapted to be moved to allow access to the cylinder and means connecting said gate and said cover whereby they may be moved simultaneously and locked in open position.
